(No Model.)

C. W. PERCIFIELD.
RIDING SADDLE.

No. 571,684.

Patented Nov. 17, 1896.

Fig. 4.

Chasnow & Co.

UNITED STATES PATENT OFFICE.

CLARENCE W. PERCIFIELD, OF RISING STAR, TEXAS.

RIDING-SADDLE.

SPECIFICATION forming part of Letters Patent No. 571,684, dated November 17, 1896.

Application filed May 19, 1896. Serial No. 592,176. (No model.)

To all whom it may concern.

Be it known that I, CLARENCE W. PERCIFIELD, a citizen of the United States, residing at Rising Star, in the county of Eastland 5 and State of Texas, have invented a new and useful Riding-Saddle, of which the following is a specification.

This invention relates to riding-saddles, and has for its object to simplify and cheapen 10 the construction of this class of devices and to increase their durability.

The improvement consists, essentially, of constructing the seat, front, rear, and middle jockeys and cantle of a single piece of stout 15 leather and having the rear quarter laced or otherwise connected in the rear of the cantle, and in such other details of construction and arrangement of the parts, which hereinafter will be more particularly set forth, illustrated, 20 and claimed.

The invention also aims to combine with a saddle a pocket or bag for carrying articles which cannot be conveniently stored about the person and which are desired to be transported in comparative safety and with comfort 25 to the rider.

For a full understanding of the merits and advantages of the invention reference is to be had to the accompanying drawings and the 30 following description.

The improvement is susceptible of various changes in the form, proportion, and the minor details of construction without departing from the principle or sacrificing any 35 of the advantages thereof, and to a full disclosure of the invention an adaptation thereof is shown in the accompanying drawings, in which—

Figure 1 is a perspective view of a riding- 40 saddle constructed in accordance with the principles of this invention. Fig. 2 is a top plan view thereof. Fig. 3 is a detail section showing the means for detachably connecting the bag or pocket to the saddle. Fig. 4 is a 45 detail view showing the rear quarter and cantle.

Corresponding and like parts are referred to in the following description and indicated in the several views of the accompanying 50 drawings by the same reference-characters.

The saddle comprises the seat 1, middle

jockeys 2, front jockeys 3, rear jockeys 4, and cantle 5, which are covered or formed from a single piece of stout leather or other suitable material, thereby obviating the provision of intermediate or connecting seams. 55 The rear jockeys 4 are extended to form the rear quarter, and are connected at their upper edges by a lace 6 or other suitable fastening. The seat 1 and rear quarter are separated by 60 the cantle 5, and the latter is protected on its rear side by a covering which is stitched to the cantle-binding. The stirrup-straps 7 pass beneath the middle jockeys 2 and the seat 1 and enter recesses formed in the inner 65 face of the side pieces of the tree. The pommel 8 is surmounted by a horn 9 and is covered by leather or similar material in the usual way, the said covering being stitched to the front portion of the seat 1 and the top 70 edge of the front jockeys 3.

By having the seat, the cantle, and the several side jockeys formed of a single piece of leather, seams are avoided and the saddle is easy and comfortable both to the animal and 75 the rider and is more durable, inasmuch as there are no threads or stitching to become worn and separated.

To prevent the seat from sinking between the side bars of the tree and preserve the appearance of the saddle, strainer-irons are provided and extend lengthwise and crosswise of the tree over the space formed between the said side bars. The position of these double strainer-irons will be readily understood by 85 any one conversant with the construction of saddles, as they come beneath the seat and opposite the space between the side bars of the tree.

The bag or pocket 10 is of usual construction, and its open side is closed by flap 11, provided with a strap 12 to engage with a buckle 13 for securing the flap when closed. Rings 14 are attached to the upper edge of the bag and are placed between the flap 11 and the back of the bag and are fastened in any substantial way, preferably by rivets, 95 which pass through the rings, the flap, and the back of the bag. Snap-hooks 15 are applied to the inner side of the rear jockey and 100 receive the rings 14 and admit of the bag being removably attached to the saddle.

Having thus described the invention, what is claimed as new is—

1. In a riding-saddle, the combination with the cantle, of rear jockeys having their upper

5 portions extended and meeting in the rear of the cantle, forming a rear quarter, and means for securing the meeting edges of the upper extensions of the rear jockeys, substantially as set forth.

10 2. In a riding-saddle having a pommel and cantle, a seat, cantle, front, rear and middle jockeys formed of a single piece, the front portion of the seat and the top edges of the front jockeys being secured to the pommel

15 covering; and the rear jockeys being extended and meeting in the rear of the cantle, and means for securing the meeting edges of the

rear jockey extensions, substantially in the manner shown and described.

3. The combination with a saddle having snap-hooks or like fastenings, of a bag, and rings placed between the flap and back of the bag and held thereto by the same means employed for connecting these parts, and the bag having detachable connection with the saddle, substantially in the manner specified.

In testimony that I claim the foregoing as my own I have hereto affixed my signature in the presence of two witnesses.

CLARENCE W. PERCIFIELD.

Witnesses:

J. H. BALES,

M. W. WYATT.
